UNITED STATES PATENT OFFICE.

DANIEL B. DANIELSON, OF MILWAUKEE, WISCONSIN.

COLUMN CONSTRUCTION.

No. 874,395.

Specification of Letters Patent.

Patented Dec. 24, 1907.

Application filed May 25, 1907. Serial No. 375,583.

To all whom it may concern:

Be it known that I, DANIEL B. DANIELSON, residing in Milwaukee, in the county of Milwaukee and State of Wisconsin, have invented new and useful Improvements in Column Construction, of which the following is a description, reference being had to the accompanying drawings, which are a part of this specification:

10 This invention has for its object to provide an improved column construction for use in building edifices, beamless floor and roof constructions and the like, and has for its object to provide a column of iron or steel frame-work with a concrete body of cement and other matter used in reinforced concrete construction work, which column will be strong, durable and simple to construct.

With the above and other objects in view 20 the invention consists in the column construction herein claimed, its parts and combinations of parts and all equivalents.

Referring to the accompanying drawings in which like characters of reference indicate 25 the same parts in different views; Figure 1 is a plan view of a framework of a pair of columns made in accordance with this invention; Fig. 2 is a side elevation thereof partly in central section; and, Fig. 3 is a transverse 30 sectional view thereof on the plane of line 3-3 of Fig. 2.

In these drawings 5 represents a series of vertical rods arranged in a circular manner to form the main frame of a column of annular or other approved section, these rods being preferably in multiples of three, so that tie wires 6 may each bind together three of the vertical rods in such a manner that they take the form of isosceles triangles. The tie 40 wires alternate with the different sets of vertical rods and are arranged at such intervals throughout the length of the column as to complete a well braced skeleton frame to receive a filling 7 of any concrete mass which 45 is molded thereon in a desirable manner.

Near the top and base of the column the frame is provided with rods 8 bent to form circular frames which are successively larger as they approach the end of the column 50 constituting a support for the base or the capital of the column.

On the top of the column some of the vertical rods are bent outwardly and radially from the axis of the column and slightly 55 downwardly from the end of the column to form a conical support and on this support

are attached in any desirable manner a series of square frames 9 of different sizes, the largest frame being first mounted on the support of outwardly bent rods, then the next size frame being mounted thereon at one-eighth turn with relation thereto with its corners overlapping the sides of the larger frame, and the succeeding frames are placed in similar arrangement with each other and 65 with the aforementioned frames so as to build up a conical framework on the support, the frames being successively smaller as they approach the end of the column. This framework is to support the floor or roof 70 above or to receive the foundation if at the foot of the column.

The largest square frame 9 of each column is connected with the corresponding square frame of each of the columns adjacent to it 75 by connecting bars 10 which start from one corner of the frame 9 of one column and pass over that column and the diagonally opposite corner of said square frame to the next column where it connects with the near 80 corner of the corresponding square frame. Thus each of the large square frames 9 has a pair of connecting bars 10 crossing it on each of its diagonals and each of said square frames is connected with each adjacent square 85 frame by two of the connecting bars, forming a rigid means for tying together all of the columns.

Such of the vertical rods 5 as are not bent over to form the conical support above referred to, preferably those which rise between the pairs of connecting bars 10, as shown in the drawings, continue upwardly above the column to constitute a means for locating the corresponding vertical rods for 90 the column on the next floor, and thus assure the columns on the different floors being in true vertical alinement.

Upon the column construction above described may be built the cement floor or roof 100 in the usual manner.

By means of this construction the stress upon the column is evenly distributed throughout by reason of the triangular tie wires connecting the vertical rods, and the 105 frames of the supports being without curves to yield are capable of sustaining a maximum stress.

What I claim as my invention is;

1. A column construction, comprising a 110 series of vertical rods arranged in circular formation, tie wires connecting the vertical

rods and forming a framework therewith, circular metal frames at the end of the column increasing in size as they approach the end of the column, and a concrete body formed 5 within and upon the framework.

2. A column construction, comprising a framework formed of a series of vertical rods arranged in circular formation, tie wires of isosceles triangular shape connecting different sets of vertical rods at intervals and forming a framework therewith, circular metal frames at the end of the column increasing in size as they approach the end of the column, and a concrete body formed within and upon 10 the framework.

3. A column, comprising a framework of vertical rods arranged in circular formation, tie wires connecting different sets of vertical rods at intervals and forming a framework 20 therewith, circular metal frames near the end of the column, a series of square metal frames surrounding the vertical rods and being of successively smaller size and each differing in position by an eighth of a turn from the 25 adjacent square frames, the vertical rods being bent outwardly and radially from the axis of the column to engage the square frames, and a concrete body formed on the framework.

4. A column, comprising a framework formed of a series of vertical rods arranged in circular formation, tie wires connecting the vertical rods together, the vertical rods being bent radially to the axis of the column and 35 downwardly from the end of the column, a series of square metal frames secured on the outwardly bent ends of the vertical bars and being of successively smaller size and each

having its corners overlapping and bearing upon the sides of the next square frame, connecting rods connecting the largest square frames of adjacent columns each passing diagonally across one of said square frames and secured to the near corner of the next square frame, and a concrete body formed on the 40 framework.

5. A column, comprising a framework formed of a series of vertical rods arranged in circular formation, tie wires connecting the vertical rods at intervals, circular metal 45 frames at the end of the column, the ends of the vertical bars being bent outwardly and radially and slightly inclined, square metal frames of different sizes mounted on said bent ends of the vertical rods and arranged 50 in the order of their size with the corners of each frame overlapping and engaging the sides of the next larger frame, and connecting bars connecting the square frames of each column with the square frames of adjacent 55 columns and each passing diagonally across one square frame and connected to the near corner of the next square frame, some of said vertical rods passing through the square metal frames and between the diagonally 60 crossing connecting bars and extending 65 above the column to serve as means for alining the column of one floor with the column of the next floor.

In testimony whereof, I affix my signature, in presence of two witnesses.

DANIEL B. DANIELSON.
